2,529,754

CIRCUIT BREAKER

Wallace T. Allen, Dearborn, Mich., assignor to
Square D Company, Detroit, Mich., a corpora-
tion of Michigan

Original application December 24, 1942, Serial No.
470,044. Divided and this application October
21, 1949, Serial No. 122,629

6 Claims. (Cl. 209—116)

1

This invention relates to current responsive thermostatic elements, and more particularly to automatic electric circuit controlling devices employing current responsive thermostatic tripping elements.

An object of the present invention is to provide an improved tripping means for an automatic electric circuit breaker.

Another object of this invention is to provide in an automatic electric circuit breaker thermostatic means for effecting improved operation of the circuit breaker on the occurrence of heavy current overloads.

Another object of this invention is to provide an automatic electric circuit breaker employing a current responsive tripping member with a part thereof being thermally effected on the occurrence of heavy current overloads, and the remainder thereof being substantially thermally unaffected except on sustained overloads.

Another object of this invention is to provide a thermal trip means for an automatic electric circuit breaker comprising a bimetallic element carrying a non-bimetallic latching element movable relative to the bimetallic element under a sustained current overload.

Other objects and features of this invention will be readily apparent to those skilled in the art from the following specification and the appended drawing illustrating certain preferred embodiments of the invention in which:

Figure 1 is a partial front elevational view of an automatic electric circuit breaker utilizing the tripping means according to the present invention and in which portions are cut away to show internal parts.

Figure 2 is a vertical sectional line taken on line II—II of Figure 1.

This application is a division of application Serial No. 470,044 in the name of Wallace T. Allen dated December 24, 1942, and which has become Patent No. 2,503,591, issued May 23, 1950.

Referring to the drawings, Figures 1 and 2 illustrate a circuit breaker mechanism specifically disclosed and claimed in the patents of John G. Jackson, No. 2,096,545 issued October 19, 1937, and No. 2,132,625 issued October 11, 1938, and both entitled "Circuit Breakers," and with a current responsive thermostatic tripping element according to the present invention. These figures illustrate one form of circuit breaker in which the tripping element, according to the present invention, may be employed although it is obvious that the tripping element is susceptible of use in any type of circuit breaker or in any other

2

apparatus in which a thermostatic latching member is employed.

The circuit breaker illustrated embodies a metallic mounting plate 1 which may be the back wall of an outer enclosing box against which is mounted an insulating base 2. Generally centrally in this base is mounted a stationary contact plate 3, as by means of a stud and carrying stationary contacts 5 adapted to cooperate with movable contacts 6 on the ends of contact blade 7. Upon ledges at the ends of the base 2 are rigidly supported connectors 8 as by means of spun over portions of metallic inserts 9 which also receive terminal studs 11. To the interior end of each of the connectors 8 is rigidly secured one end of a bimetallic member 27 as by means of an adjusting means generally designated at 13.

As shown in Figure 2, the tripping member comprises a bimetallic member 27 to which is rigidly secured by welding at a single weld point the non-bimetallic or thermally non-active element 28 having the end thereof bent as at 29 to provide a latch for engagement with a tip 19 of the contact blade 7. The single point of weld is indicated in Figure 2 in conventional manner by a small x at the juncture between the joined elements 27 and 28.

A compression spring 18 biases the movable contact 6 carried by the blade 7, against the stationary contact 5, and biases the tip 10 of the blade against the latch 29 of the non-bimetallic member 28. A U-shaped member 19 having legs of dissimilar length is guided by formations in the base for rectilinear movement at right angles thereto. The longer leg of the member 19 is slotted to receive the blade 7, and the blade at its top edge is provided with a notch 21 received within the top edge of the slot. A second notch 22 is provided in the front edge of the blade, and is adapted to engage a shorter leg of the member 19 to serve as a stop for the blade upon rotation as hereinafter described. An operating handle 23 pivotally mounted on a shaft 24 has an interior cam surface which effects rectilinear movement of the member 19, which cam surface includes a flat staple portion 25 and a resetting tip 26.

The blade 7 of Figure 2 is in the normal "on" position. To move the parts to the manual "off" position, the handle is rotated counterclockwise until the flat surface 25 engages the top surface of the member 19 which produces a stable position in which the member 19 has been moved toward the bottom of the base and has separated the movable contact at the end of the associated blade 7 from its cooperating stationary contact 5.

In the automatic operation of the breaker, this invention provides for a quicker tripping of the switching parts on the occurrence of short circuits and heavy current overloads than previously obtained in circuit breakers, with consequent added protection to the circuit breaker parts, and to the circuit controlled thereby. This feature of more rapid tripping is effected in a manner now to be described.

The breaker is so constructed that on moderate overload the bimetallic element 27, a substantial portion of which is in series circuit with the contacts, is heated by the current, this heat being transmitted to the non-series portion by conduction whereby this non-series portion flexes. This flexure causes the latch end 29 of the non-active element 28 to move toward its engagement with the blade 7; that is, as the non-series part of bimetal 27 is bowed upon a rise in temperature, element 28 will assume a position tangent to the arc of bimetal 27 at point of juncture x to move latch 29 toward tip 10 of blade 7 to tend to oppose the releasing movement of element 27 and to tend to maintain the latch 29 in engagement with the tip 10 until the attainment of the rated current for the device. After the attainment of a predetermined degree of overload, the bimetal 27 will flex sufficiently to move the latch 29 off of the tip 10 of the contact blade 7, whereupon this blade rotates in a counterclockwise direction about the engagement of the notch 21 with the member 19, and under the bias of spring 18 into the contacts disengaged position, thus interrupting the circuit through the breaker mechanism. Upon heavy current overload, the non-series portion is not heated enough to flex as the breaker trips quickly due to flexing of the current carrying portion of bimetal 27 by the heat generated by the current flow therethrough. To reset the parts after an automatic release, the handle is rotated past the "off" position until the resetting tip 26 is on the top surface of member 19, in which position the contact blade 7 will have engaged the bottom of the arc chamber and moved back into position to engage this latch 29. If the bimetal 27 has cooled sufficiently to assume its normal position, releasing the handle will then place the parts in the normal "off" position, whereupon clockwise rotation of the handle will again permit the parts to assume the positions shown in Figure 2.

The tendency of the tripping element to maintain engagement with a contact blade on moderate overload permits the employment of a lesser overlap between latch and blade than ordinarily required to obtain the desired rating or calibration. With the use of a lesser overlap, it is obvious that on the occurrence of a heavy overload, the latching means having a lesser distance to move to effect release of the blade 7, will effect tripping in a lesser time. Lessening the trip time on the occurrence of heavy overloads is definitely a desirable feature for it lessens the possibility of damage to the circuit breaker parts by the heavy overload current.

It is evident then that a circuit breaker, by employing a tripping member of a type described herein in which a portion opposes release of the contact blade on the occurrence of a moderate overload, will retain its given rating and will not trip out too quickly on moderate overloads and yet will effect a materially faster release of the switching parts on the occurrence of a short circuit or heavy overload, and therefore results in

better protection to the circuit breaker and its associated circuit.

While a certain preferred embodiment of the invention has been specifically disclosed, it is understood that the invention is not limited thereto, and many variations will be readily apparent to those skilled in the art and the invention is to be given its broadest possible interpretation within the terms of the following claims.

What is claimed is:

1. An automatic circuit breaker, separable contacts, a switching member for effecting separation of the said contacts to open the circuit through the breaker, a thermostatic member for initiating operation of said switching member, a flexible lead interconnecting said thermostatic member and said switching member, said flexible lead being secured to said thermostatic member intermediate the ends thereof whereby but a portion of said thermostatic member is in series circuit with said contacts, a thermally inactive member secured to that portion of said thermostatic member which is not in series circuit with said contacts, said thermally inactive member being attached to said thermostatic member only near one extremity of said thermally inactive member and having a latching surface near the opposite extremity of said thermally inactive member engageable with said switching member, said series circuit portion of said thermostatic member being movable toward releasing position on the occurrence of moderate overload current, at least that portion of said thermally inactive member having the latching surface also being movable relative to said thermostatic member on said occurrence of a moderate overload current so as to tend to maintain said latching surface in engagement with said switching member.

2. In an automatic electric circuit breaker, a stationary contact, a movable contact, a switching member for moving said movable contact into and out of engagement with said stationary contact, a manual member for moving said switching member to perform the switching operation, and means for causing automatic separation of said contacts, said means comprising a bimetallic element and a member carried thereby, said member being attached only near one of its ends to said bimetallic element and having a latching portion near its unattached end engageable with said switching member to normally maintain it in position for operation by said manual member, said bimetallic element on the occurrence of a predetermined overload current flexing to move said member carried thereby to a position tangent to the arc formed by said bimetallic element whereby said latching portion is moved relative to said bimetallic element so as to tend to maintain engagement with said switching member.

3. In an automatic electric circuit breaker, a stationary contact, a movable contact, a switching member for moving said movable contact into and out of engagement with said stationary contact, a manual member for moving said switching member to perform the switching operation, and means for causing automatic separation of said contacts, said means comprising a bimetallic element fixed at one end, and a thermally inactive element secured only at the free end of said bimetallic element and directed toward the fixed end of said bimetallic element, said thermally inactive element having a latching portion at its unsecured end engageable with said switching member to normally maintain it

in position for operation by said manual member, said bimetallic element on the occurrence of a predetermined overload current flexing in a first direction to move said thermally inactive element to a position tangent to the arc formed by said bimetallic element to move said latching portion relative to said bimetallic element in a direction to tend to maintain engagement with said switching member.

4. In an automatic electric circuit breaker, separable contacts controlling the flow of current through the breaker, and thermally responsive means for initiating operation of said contacts to separated position in response to the passing of overload currents through the breaker, said means including a bimetallic member having fixed and free ends, an electrical conductor connected to said bimetallic member intermediate its ends and to one of said contacts thereby placing only the part of said bimetallic member between its fixed end and the point of connection of said conductor in series circuit with the contacts so as to be traversed by the current passing through the breaker whereby said part of the bimetallic member is directly heated by current flow therethrough, a thermally unaffected latch member, means joining said latch member only near one extremity thereof to the non-series portion of said bimetallic member the latch on said latching member being near the extremity thereof opposite that joined to said bimetallic member, the bimetallic member being quickly heated upon occurrence of a short circuit current to rapidly move said latch member to unlatched position, the non-series portion of said bimetallic member being heated by conduction from said series portion upon the occurrence of a moderate overload and flexing in a direction to move said latching portion toward latched position.

5. In an automatic electric circuit breaker, separable contacts controlling the flow of current through the breaker, and thermally responsive means for initiating operation of said contacts to separated position in response to the passage of overload currents through the breaker, said means including a bimetallic member having fixed and free ends, an electrical conductor connected to said bimetallic member intermediate its ends and to said contacts thereby placing only the part of said bimetallic member between its fixed end and the point of con-

nection of said conductor in series circuit with the contacts so as to be traversed by the current passing through the breaker whereby said part of the bimetallic member is directly heated by current flow therethrough, a thermally non-responsive latching member, means connecting the latching member to the non-series portion of said bimetallic member at a single point remote from the current carrying portion thereof, the latch portion of said latching member being remote from the point at which said latching member is connected to said bimetallic member, the bimetallic member being rapidly heated upon the occurrence of a substantial overload to quickly move the latch portion of said latching member toward unlatched position, the non-series portion of said bimetallic member being heated by conduction from said series portion upon occurrence of a moderate overload and flexing thereby to move the latch portion of said latching member away from the bimetallic member to effect an overall unlatching movement which is a differential of the movements of the bimetallic member and the latch portion of the latching member.

6. In an automatic circuit breaker, separable contacts controlling the flow of current through the breaker, thermally responsive means for initiating the opening operation of said contacts upon the passage of overload current through the breaker, said means including a bimetallic member having fixed and free ends, means for heating at least that portion of said bimetallic member adjacent its fixed end, a rigid latch member, means connecting one extremity of said latch member to the free end of said bimetallic member, said latch member having a latching portion near the extremity of said latch member opposite to that affixed to said bimetallic member, the latching portion of said latching member being movable relative to said bimetallic member upon the occurrence of predetermined thermal conditions in the circuit breaker.
